PREPARATORY FIBER OPENER

John H. Senior, Germantown, and Harmon B. Riehl, Norristown, Pa., assignors to Proctor & Schwartz, Inc., Philadelphia, Pa., a corporation of Pennsylvania

Application May 26, 1950; Serial No. 164,501

10 Claims. (Cl. 19—79)

1
The present invention relates to new and useful improvements in fibre treating apparatus and more particularly to new and useful improvements in apparatus for breaking up large clumps or masses of fibres and then feeding them to further fibre-treating apparatus such as a carding machine.

Prior to the present invention fibres discharged from a breaker feed were tangled and not sufficiently opened with the result that they required extensive picking action before they were suitable for use.

With the foregoing in mind, the principal object of the present invention is to provide a novel initial fibre opening device which operates to reduce the masses of fibres to smaller increments before feeding them to other fibre treating apparatus.

Another object of the present invention is to provide a novel preparatory opener which, in addition to breaking up large masses or clumps of fibres, also operates to pre-card the fibres before they are discharged from the opener.

A still further object of the present invention is to provide novel apparatus of the type described having the features and characteristics set forth which is entirely efficient and effective in operation and use.

These and other objects of the present invention and the various features and details of the construction and operation thereof are hereinafter fully set forth and described with reference to the accompanying drawings, in which:

Fig. 1 is a schematic longitudinal sectional view of the preparatory opener made in accordance with the present invention;

Fig. 2 is an enlarged fragmentary sectional view of a portion of the device shown in Fig. 1, showing the fibres being acted on by the various rolls;

Fig. 3 is a side elevational view of a portion of the preparatory opener showing the arrangement of the drive for the various rolls thereof; and

Fig. 4 is an enlarged sectional view taken on line 4—4, Fig. 2.

Referring more particularly to the drawings, reference numeral 1 designates generally a preparatory fibre opener to which large masses or clumps of fibres are fed. The preparatory opener 1 operates to break down these large masses or clumps of fibres and pre-cards the fibres to form a mat 2 of substantial thickness in which all of the fibres are partially aligned in preparation to being fed to some further fibre treating apparatus, such as a card (not shown).

The large masses or clumps of fibres are fed to

2
the preparatory opener 1 by a feed conveyor 3 which deposits the fibres on a generally horizontal apron conveyor 4. The apron conveyor 4 is intermittently fed by means of a crank arm 5 carried on a shaft 6 which pulls a pawl 7 by means of a connecting link 5a back and forth over a ratchet wheel 8 secured to the rear shaft 9 of the apron conveyor 4. As the pawl 7 is pulled forward it engages the rearwardly inclined teeth of the ratchet wheel 8 and moves the apron conveyor forward, and as the pawl 7 is forced backward it is disengaged from the teeth of the ratchet wheel and the apron conveyor does not move. The apron conveyor 4 is carried by sprocket wheels 4a and 4b mounted on the shafts 9 and 6, respectively. The sprocket 4b is loosely mounted on shaft 6 while the sprocket 4a is fixedly secured to the rear shaft 9 and driven thereby.

The fibres are picked from the apron conveyor 4 by an upwardly inclined pin conveyor 10 which consists of a series of horizontal slats 11, each of which carries a plurality of forwardly inclined pins 12. The apron conveyor is carried by sprockets mounted on relatively spaced horizontal upper and lower shafts 13 and 14, respectively, and is continuously driven thereby.

Positioned adjacent the top of the upper run of the pin conveyor 10 is a retractable pin beater 17 of the type shown and described in U. S. Patent No. 2,372,543, issued March 27, 1945. The retractable pin beater 17 is mounted on a shaft 17a and consists of a plurality of rows of retractable pins 18 which travel in an opposite direction to the pins 12 of the pin conveyor 10. The retractable pin beater 17 operates to remove excess fibres which are picked up by the pin conveyor so that a mat of substantially uniform thickness is formed on the pin conveyor.

The fibres removed by the retractable pin beater 17 are first deposited upon a plurality of elongated fingers 19 which are positioned laterally adjacent to the upward run of the pin conveyor 10. The fingers 19 are rotatably carried on a shaft 20 extending transversely across the preparatory opener. Also connected to the shaft 20 is a counterweight 22 which normally holds the fingers in the forward or upper position shown in Fig. 1 and thus presses the fibres thereon against the pin conveyor 10.

As the mass of fibres between the pin conveyor 10 and the fingers 19 builds up the fingers and the counterweight 22 are overbalanced by the weight of the fibre so that said fingers rotate about the axis of the shaft 20 in a clockwise direction. This in turn actuates in the downward

3

direction a connecting link 23 which is also secured to the shaft 20 by means of a crank arm 24. The lower end of the connecting link 23 is secured to a bracket member 25 which carries a cover plate 26 thereon and as the link 23 moves downward, the cover plate 26 is rotated about the axis of the ratchet wheel 8 and covers the teeth thereon preventing engagement of the ratchet wheel 8 by the pawl 7. This controls the feed of the fibres to the pin conveyor 10. When the fingers 19 are in their extreme downward position as indicated in broken lines in Fig. 1, the teeth of the ratchet wheel 8 are completely covered by the cover plate 26 thereby precluding any forward motion of the apron conveyor 4. Alternatively, when the fingers are in their extreme forward or upper position shown in Fig. 1, the ratchet is entirely uncovered allowing the maximum amount of feed of the apron conveyor 4 and in any intermediate position of the fingers 19 the ratchet wheel 8 is partially covered by the cover plate 26 thereby controlling the amount of forward feed of the apron conveyor 4.

Positioned adjacent the upper end of the pin conveyor 10 is a worker roll 28 carried by a shaft 29 which extends transversely across the preparatory opener. The worker roll 28 rotates in a counterclockwise direction at a substantially slower peripheral speed than the pin conveyor 10 and carries a plurality of rearwardly inclined pins 30 thereon. As shown in Fig. 4 the rows of pins 30 on the worker roll 28 are staggered with respect to the rows of pins 12 on the pin conveyor 10 and an arc connecting the outer surfaces of the pins 30 substantially overlaps a similar arc connecting the outer edges of the pins 12 on the pin conveyor 10. The pins 30 on the worker roll 28 engage the fibres carried by the pin conveyor 10 and tend to straighten them and partially align them.

Positioned adjacent the worker roll 28 and the pin conveyor 10 is a second retractable pin beater 31 which is carried on a shaft 32. This second retractable pin beater 31 is similar to the aforementioned retractable pin beater 17 and operates to remove the fibres from the worker roll 28 and pin conveyor 10 and then deposit them on a pin cylinder 33. The pin cylinder 33 is driven by a shaft 34 in a clockwise direction and has a plurality of rows of forwardly inclined pins 35 thereon.

Cooperable with the pin cylinder 33 is a second worker roll 37 carried by a shaft 38 and driven in a counterclockwise direction. A plurality of rows of rearwardly inclined pins 39 are secured to the worker roll 37. The worker roll 37 is positioned so that there is slight clearance between the pins 39 thereon and the pins 35 of the pin cylinder 33. The peripheral speed of the worker roll 37 is substantially slower than that of the pin cylinder 33, and as the fibres pass between the two rolls they are combed so that fibres discharged therefrom are substantially aligned.

A blade beater 41 secured to a shaft 42 rotating in a counterclockwise direction is positioned adjacent to the pin cylinder 33 and operates to remove the fibres therefrom. As the fibres are removed from the pin cylinder 33 they are deposited on a discharge conveyor 43 which carries the fibres to some further fibre treating apparatus.

Extending transversely across the preparatory opener are a pair of guides 44 and 45 which are used to direct the fibres either forward onto the discharge conveyor 43 or backwards to a lower

guide 46 from which the fibres will be picked up by the pin conveyor. The fibres directed backwards by the guide 45 are those which have dropped off from the pin conveyor 10.

The drive mechanism for the various rolls is shown in Fig. 3 of the drawings. The driving means (not shown) is connected to shaft 47 which in turn drives shaft 48 by some suitable means, for example, a V-belt 50. The first retractable pin beater 17 is driven by a belt 51 connecting shafts 17a and 48 as shown. The drive shaft 48 extends transversely of the preparatory opener 10 and has a pair of pulleys 52 and 53 secured thereto at its opposite end. The pulleys 52 and 53 drive a second pair of pulleys 54 and 55 respectively through suitable belt connections as shown.

The pulley 54 is secured to a shaft 57 on which is mounted a pinion 58. Cooperable with the pinion 58 is a gear 59 secured to the shaft 13 which drives the pin conveyor 10. The pin conveyor 10 is mounted at its lower end on the shaft 14 and in turn drives the shaft 14. The crank arm 5 is driven from shaft 14 by a pair of sprockets 61 and 62 carried by shafts 14 and 6, respectively, and interconnected by a chain 63.

The upper shaft 13 of the pin conveyor has a pair of sprockets 65 and 66 mounted thereon which in turn drive chains 67 and 68, respectively. The one chain 67 connects the shaft 13 with the idler wheel 69 and the shafts 29 and 38 which carry the two worker rolls 28 and 37, respectively. The other chain 68 drives the shaft 34 which carries the pin cylinder 33. The blade beater 41 is driven from the shaft 32 by a belt 70 and pulleys 71 and 72 carried respectively on shafts 42 and 32.

From the foregoing it will be observed that the present invention provides a novel preparatory opener which in addition to breaking up large masses or clumps of fibres also operates to align the fibres before they are discharged from the breaker. Furthermore the present invention provides a novel initial opening device which also gives a preliminary carding to the fibres.

While certain embodiments of the invention have been illustrated and described herein, it is not intended to limit the invention to such disclosures, and changes and modifications may be incorporated and embodied therein within the scope of the following claims.

We claim:

1. In a preparatory opener comprising a feed conveyor on which large masses and clumps of fibres are placed, an upwardly inclined pin conveyor adjacent one end of said feed conveyor to remove said fibre therefrom, a retractable pin beater to remove excess fibres from said pin conveyor, a worker roll adjacent the upper end of said pin conveyor to align said fibres with the direction of travel of said pin conveyor, a second retractable pin beater at the opposite side of said worker from said first retractable pin beater to remove said fibres from said pin conveyor and worker roll, and a pair of pin cylinders rotating in opposite directions with different peripheral speeds to receive the fibres from said second retractable pin beater and produce a preliminary carding of the fibres discharged from said pin conveyor.

2. In a preparatory opener comprising a feed conveyor on which large masses and clumps of fibres are placed, an upwardly inclined pin conveyor adjacent one end of said feed conveyor to remove said fibre therefrom, a retractable pin

beater to remove excess fibres from said pin conveyor, a worker roll adjacent the upper end of said pin conveyor to align said fibres with the direction of travel of said pin conveyor, a second retractable pin beater at the opposite side of said worker from said first retractable pin beater to remove said fibres from said pin conveyor and worker roll, a pair of pin cylinders rotating in opposite directions with different peripheral speeds to receive the fibres from said second retractable pin beater and produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

3. In a preparatory opener comprising a feed conveyor on which large masses and clumps of fibres are placed, mechanism to drive said feed conveyor, an upwardly inclined pin conveyor adjacent the forward end of said feed conveyor to remove said fibres therefrom, means to remove excess fibres from said pin conveyor, a plurality of fingers laterally spaced from the pin conveyor and cooperable therewith to receive and collect between said fingers and pin conveyor the excess fibres removed from said pin conveyor, said fingers operable to be moved outward away from the pin conveyor by the collected fibres, means connecting said fingers with said mechanism actuatable by movement of said fingers to control the motion of said feed conveyor, a worker roll adjacent the upper end of said pin conveyor to align said fibres with the direction of travel of said pin conveyor, a pair of pin cylinders rotating in opposite directions with different peripheral speeds to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

4. In a preparatory opener comprising a feed conveyor on which large masses and clumps of fibres are placed, mechanism to drive said feed conveyor, an upwardly inclined pin conveyor adjacent the forward end of said feed conveyor to remove said fibres therefrom, means to remove excess fibres from said pin conveyor, a plurality of fingers laterally spaced from the pin conveyor and cooperable therewith to receive and collect between said fingers and pin conveyor the excess fibres removed from said pin conveyor, said fingers operable to be moved outward away from the pin conveyor by the collected fibres, means connecting said fingers with said mechanism actuatable by movement of said fingers to control the motion of said feed conveyor, a worker roll adjacent the upper end of said pin conveyor to align said fibres with the direction of travel of said pin conveyor, a retractable pin beater to remove said fibres from said pin conveyor, a pair of pin cylinders to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

5. In a preparatory opener comprising a feed conveyor on which large masses and clumps of fibres are placed, drive mechanism to drive said feed conveyor, an upwardly inclined pin con-

veyor adjacent the forward end of said feed conveyor to remove said fibres therefrom, means to remove excess fibres from said pin conveyor, a plurality of fingers laterally spaced from the pin conveyor and cooperable therewith to receive and collect between said fingers and pin conveyor the excess fibres removed from said pin conveyor, a weight operable to bias said fingers toward the pin conveyor arranged to be overbalanced by a predetermined weight of the collected fibres to cause the fingers to be actuated away from the pin conveyor, means connecting said fingers with said drive mechanism actuatable by movement of said fingers to control the motion of said feed conveyor, a worker adjacent the upper end of said pin conveyor to align said fibres with the direction of travel of said pin conveyor, a pair of pin cylinders to produce a preliminary carding of the fibres discharged from said pin conveyor, and a discharge conveyor on which said fibres are deposited to remove the fibres from the opener and feed them to further fibre processing apparatus.

6. In a preparatory opener comprising a feed conveyor on which large masses and clumps of fibres are placed, drive mechanism to drive said feed conveyor, an upwardly inclined pin conveyor adjacent the forward end of said feed conveyor to remove said fibres therefrom, means to remove excess fibres from said pin conveyor, a plurality of fingers laterally spaced from the pin conveyor and cooperable therewith to receive and collect between said fingers and pin conveyor the excess fibres removed from said pin conveyor, a weight operable to bias said fingers toward the pin conveyor arranged to be overbalanced by a predetermined weight of the collected fibres to cause the fingers to be actuated away from the pin conveyor, means connecting said fingers with said drive mechanism actuatable by movement of said fingers to control the motion of said feed conveyor, a worker roll adjacent the upper end of said pin conveyor to align said fibres with the direction of travel of said pin conveyor, a pair of pin cylinders rotating in opposite directions to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

7. In a preparatory opener comprising a feed conveyor on which large masses and clumps of fibres are placed, drive mechanism to drive said feed conveyor, an upwardly inclined pin conveyor adjacent the forward end of said feed conveyor to remove said fibres therefrom, means to remove excess fibres from said pin conveyor, a plurality of fingers laterally spaced from the pin conveyor and cooperable therewith to receive and collect between said fingers and pin conveyor the excess fibres removed from said pin conveyor, a weight operable to bias said fingers toward the pin conveyor arranged to be overbalanced by a predetermined weight of the collected fibres to cause the fingers to be actuated away from the pin conveyor, means connecting said fingers with said drive mechanism actuatable by movement of said fingers to control the motion of said feed conveyor, a worker roll adjacent the upper end of said pin conveyor to align said fibres with the direction of travel of said pin conveyor, a retractable pin beater to remove said fibres from said pin conveyor, a pair of pin cylinders to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

of pin cylinders to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

8. In a preparatory opener comprising a feed conveyor on which large masses and clumps of fibres are placed, ratchet mechanism to intermittently drive said feed conveyor, an upwardly inclined pin conveyor adjacent the forward end of said feed conveyor to remove said fibres therefrom, a retractable pin beater to remove excess fibres from said pin conveyor, a plurality of fingers laterally spaced from the pin conveyor and cooperable therewith to receive and collect between said fingers and pin conveyor the excess fibres removed from said pin conveyor, said fingers operable to be moved outward away from the pin conveyor by the collected fibres, means connecting said fingers with said ratchet mechanism actuatable by movement of said fingers to control the motion of said feed conveyor, a worker roll adjacent the upper end of said pin conveyor to align said fibres with the direction of travel of said pin conveyor, a second retractable pin beater to remove said fibres from said pin conveyor, a pair of pin cylinders rotating in opposite directions to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

9. In a preparatory opener comprising a feed conveyor on which large masses and clumps of fibres are placed, ratchet mechanism to intermittently drive said feed conveyor, an upwardly inclined pin conveyor adjacent the forward end of said feed conveyor to remove said fibres therefrom, a retractable pin beater to remove excess fibres from said pin conveyor, a plurality of fingers laterally spaced from the pin conveyor and cooperable therewith to receive and collect between said fingers and pin conveyor the excess fibres removed from said pin conveyor, a weight operable to bias said fingers toward the pin con-

veyor arranged to be overbalanced by a predetermined weight of the collected fibres to cause the fingers to be actuated away from the pin conveyor, means connecting said fingers with said ratchet mechanism actuatable by movement of said fingers to control the motion of said feed conveyor, a worker roll adjacent the upper end of said pin conveyor to align said fibres with the direction of travel of said pin conveyor, a second retractable pin beater to remove said fibres from said pin conveyor, a pair of pin cylinders rotating in opposite directions to produce a preliminary carding of the fibres discharged from said pin conveyor, a beater roll to remove the fibres from said pin cylinders, and a discharge conveyor on which said fibres are deposited to remove the fibres from the opener and feed them to further fibre processing apparatus.

10. In a preparatory opener comprising a feed conveyor on which large masses and clumps of fibres are placed, an upwardly inclined pin conveyor adjacent one end of said feed conveyor to remove said fibre therefrom, means adjacent said pin conveyor operable to remove excess fibres therefrom, a worker roll adjacent said pin conveyor to align the fibres remaining thereon with the direction of travel of the pin conveyor, a beater adjacent said pin conveyor and worker roll operable to remove fibres from both said pin conveyor and worker roll, and a pair of pin cylinders rotating in opposite directions with different peripheral speeds disposed to receive the fibres removed by said beater and operable to produce a preliminary carding of said fibres.
